[57] CLAIM

The ornamental design for a pair of wings for an airplane, substantially as shown and described.

DESCRIPTION

FIG. 1 is a perspective view of a pair of wings for an airplane showing my new design;

FIG. 2 is a top plan view of a left wing assembly;

FIG. 3 is a side elevation view of a left wing assembly;

FIG. 4 is a bottom plan view of a left wing assembly;

FIG. 5 is a front elevation view of a left wing assembly;

FIG. 6 is a rear elevation view of a left wing assembly. The right wing assembly is a mirror image of the left wing assembly shown in FIGS. 2 through 6.

The dotted lines in FIG. 1 are for illustrative purposes only and form no part of the claimed design.
